UNITED STATES PATENT OFFICE.

ABRAM MOSES, OF BALTIMORE, MARYLAND.

VISIBLE-CARD INDEX.

1,126,062.

Specification of Letters Patent. Patented Jan. 26, 1915.

Application filed November 5, 1914. Serial No. 870,446.

To all whom it may concern:

Be it known that I, ABRAM MOSES, of Baltimore, State of Maryland, have invented certain new and useful Improvements in 5 Visible-Card Indexes; and I do hereby declare the following to be a full, clear, and exact description of the invention, such as will enable others skilled in the art to which it appertains to make and use the same.

10 My invention consists in the novel features hereinafter described with reference to the accompanying drawings in which I have illustrated one form in which the invention may be embodied, which has been 15 selected by me for the purpose of illustrating the invention, and the said invention is fully disclosed in the following description and claims.

Referring to the said drawings,—Figure 20 1 is an elevation partly in section, of a visible card index frame, embodying my invention, and designed particularly for supporting index cards in uniform arrangement, so that the titles or names upon the 25 upper portion of the successive cards are visible. Fig. 2 is a vertical sectional view of the same. Fig. 3 is an enlarged fragmentary vertical sectional view of the frame showing the method and means of supporting 30 the cards with their upper edges one above the other. Fig. 4 is a fragmentary view of one of the index cards, showing one of the supporting clips attached. Fig. 5 is a side and front view of one of the 35 supporting clips. Fig. 6 is a horizontal sectional view of the frame.

The object of my invention is to provide a visible card index device adapted especially for use in establishments where it is 40 desirable to ascertain, for instance, if a certain person has an account with the establishment, or other such information, and where it is necessary to obtain such information in the least possible time. It is to be 45 understood, however, that the device may also be employed in any relation where a visible card index is desired and in other relations in which its use will be advantageous, or desirable.

50 In carrying out my invention, I employ an extensible frame, the separate parts of which are preferably stamped out of a single sheet of material and bent to the desired form, and to combine with said frame 55 the index cards, each of which is provided with means to support the card behind in

elevated position, whereby, the upper edges of the cards containing the names or titles are visible from the exterior of the front side of the frame.

Visible card files, heretofore known, have two serious objections, viz., lack of sufficient flexibility and their incapability of use with ordinary cards, a specially designed card being necessary. Appertaining to the 65 first defect the frames are inelastic and when a frame is full of cards and one or more cards have to be added to the files, they cannot be introduced into the full frame but another frame must be employed.

70 My invention contemplates an extensible frame whereby one or a number of cards may be inserted at any point in a full frame, by simply adjusting the length of the 75 frame. In regard to the second objection to the visible card filing system, my invention anticipates the employment of ordinary stock cards, and as it is often desirable to change from the ordinary file to the visible 80 one, such change can be quickly made with my improved device without the necessity of re-writing the cards, by simply attaching two of my improved supporting clips to each card.

85 In the drawings 1 designates my improved index frame, which is preferably composed of sheet metal suitably cut and formed, and consists of two sections 2 and 3, one of which slides on the other, and said 90 frames are adjustably secured together by eye screws 4 which engage screw threaded apertures 5 provided in both of the sections. The eye screws 4 also act as one part of 95 hinges for supporting the frame, the other part of the hinges being shown at 6.

100 Each of the sections comprise side bars 7, a top bar 8 and a bottom bar 9, and the bottom bar of the section 2 forms a support for the lower card, hereinafter described. The side bars 7 are bent in the form of hook shaped portions 10, and extend rearwardly in the shape of oblique portions 11 which are integral with the rear portions 12. It will be seen from the foregoing, when taken 105 in connection with the drawing, that the frame is made of two sections, which are adjustable relative to one another to accommodate different numbers of cards, by means of the eye screws 4.

110 Ordinary stock cards 13 are adapted to be used in connection with my filing frame,

- by applying supporting clips 14 to the lateral edges of said cards near the bottom edge; and each of these clips 14 is preferably stamped out of a single piece of metal 5 and consists of a supporting part 15 having a rearwardly bent tongue 16 provided with an oblique edge 17, and a securing part 18, which has a tongue 19 for insertion in a slot 20 in the part 15 when the clip is bent 10 on the line 21. After the clips have been applied to the cards the cards are inserted in the frame, by simply flexing said cards and allowing their lateral edges to enter the hook shaped parts 10. The oblique 15 edges 17 of the clips will then engage the oblique portions 11 of the frame and be guided thereby and the sharp ends of the tongues 16 will engage the rear portions 12 of the frame.
- 20 It will be seen that the clips of each card act as a support for the card above so that the upper edges of the cards containing the names will all be apparent from the exterior and should it be necessary to insert a 25 card between two cards already in the frame the same can be accomplished by raising the upper card of the two cards between which the additional card is to be inserted.
- While I have selected one embodiment of 30 my invention for the purpose of illustrating the same, I do not desire to be limited to the exact details of construction shown and described, as variations therein may be made without departing from the spirit of 35 the invention.
- What I claim and desire to secure by Letters Patent is:—
- 40 1. In a visible card index, a frame, cards movable in said frame and guided thereby, and separate means secured to each of said cards for supporting the card above, whereby cards may be inserted between two of said cards without removing the same from the frame.

2. A visible card index device comprising an extensible frame, and cards provided with supporting clips for the cards above, mounted in said frame. 45
3. A visible card index device comprising a frame formed of two sections adjustably connected together; and cards provided with supporting clips for the cards above, mounted in said frame. 50
4. A visible card index device comprising a frame consisting of two sections, one of which slides on the other, means for adjustably securing said sections together, and cards carried by said frame, each of said cards being provided with a supporting clip for holding the card above in elevated position. 55
5. A visible card index device comprising a frame having its lateral edges provided with hook shaped portions which are integral with oblique portions, and cards carried by said frame, each of said cards being provided with clips having rearwardly bent tongues adapted to engage said oblique portions of the frame and be guided thereby, and the clips of each card being adapted to 60 support the card above in elevated position. 65
6. A clip for use in visible card filing systems consisting of a plate stamped from a single sheet of material and bent to form a supporting side and a securing side, said 70 supporting side being provided with a rearwardly extending tongue having an oblique edge and also with a slot, and said securing side being provided with a tongue adapted to pass through a card and through 75 the slot to secure the clip upon a card. 80

In testimony whereof, I have signed this specification in the presence of two subscribing witnesses.

ABRAM MOSES.
